UNITED STATES PATENT OFFICE

149,667

DESIGN FOR A HOUSEBOAT

Burdett H. O'Connor, Montclair, N. J.

Application January 18, 1947, Serial No. 136,247

Term of patent 3½ years

(Cl. D71—1)

To all whom it may concern:

Be it known that I, Burdett H. O'Connor, a citizen of the United States of America, residing at Montclair, in the county of Essex, State of New Jersey, have invented a new, original, and ornamental Design for a Houseboat, of which the following is a specification, reference being had to the accompanying drawing, forming part hereof.

In the drawing:

Both sides of the houseboat are substantially the same as that shown in Figure 1.

I claim:

The ornamental design for a houseboat, as shown and described.

BURDETT H. O'CONNOR.
